YORK, A CORPORATION OF NEW YORK.

TYPE-WRITING MACHINE.

1,197,336.

Specification of Letters Patent.

Patented Sept. 5, 1916.

Application filed April 3, 1915. Serial No. 18,987.

To all whom it may concern:

Be it known that we, CHARLES J. BOND and HUBBARD N. JOSLEYN, citizens of the United States, and residents of Syracuse, in 5 the county of Onondaga and State of New York, have invented certain new and useful Improvements in Type-Writing Machines, of which the following is a specification.

Our present invention relates primarily to 10 the universal bar mechanism of typewriting machines and its main object is to provide new and improved mechanism of the character specified.

To the above and other ends which will 15 hereinafter appear, our invention consists in the features of construction, combinations of devices and arrangements of parts herein-after described and particularly pointed out in the claims.

20 In the accompanying drawings which illustrate the preferred form of our invention, applied to a typewriting machine having some characteristics of the Monarch typewriter, Figure 1 is a front to rear vertical sectional view of said typewriting machine. Fig. 2 is a fragmentary detail view on a larger scale, said view being partly in side elevation and partly in section and showing features of the universal bar construction. Fig. 3 is a horizontal sectional view taken on a plane indicated by the dotted line x in Fig. 1 and looking downward. Fig. 4 is a top plan view, partly in section, showing various parts as they appear when 25 the top plate is removed. Fig. 5 is a vertical transverse sectional view taken on a plane indicated by the dotted line y — y in Fig. 1 and looking in the direction of the arrow at said line. Fig. 6 is a rear elevation, 30 partly in section, showing certain of the escapement devices. Fig. 7 is a fragmentary perspective view showing the novel universal bar mechanism and associate parts.

As shown in the drawings, the main frame 45 of the machine comprises a base 1, posts 2 and a top plate 3. Rising from the top plate are standards 4 to which are fixed upper and lower grooved rails or track-ways 5 and 6, said rails co-operating through anti-friction balls 7 with the rear bar or slide 8 of a carriage or platen carrier. Said carriage further comprises forwardly extending end bars 9 rigid with the bar 8 and providing bearings for a rotary platen 10. Co-

operative with the front face of said platen 55 are a segmentally arranged series of type bars 11, each type bar having fixed to its free end a block 12 provided with two types, the inner type 13 being a lower case type and the outer type 14 or the one farthest 60 from the pivot of the type bar being an upper case type, thus reversing the usual order of the types in the Monarch machine. The type bars are preferably pivoted on a common pivot wire 15 which is mounted on a 65 shiftable type bar segment 16. The type bar construction and mounting are not herein described in detail as they are the joint invention of Hubbard N. Josley and John W. Koerner and form the subject-matter of 70 their application, Serial No. 19,470, filed April 6, 1915. Each type bar is connected by a link 17 with an upright sub-lever 18 which is fulcrumed at 19 on a key lever 20, said sub-lever being slotted at 21 near its 75 lower end to co-operate with a fixed abutment 22. The set of key levers 20 are fulcrumed on a plate 23 mounted in the rear portion of the base and each key lever is provided with a key cap or button 24.

80 Near their outer end portions the type bars are normally supported by a curved segmental rest 25 which is mounted on a frame 26 screwed to bars or rods 27 rigid with and projecting forward from the segment 16 near each side thereof. Said segment 16 and said rest 25 are comprised in a type bar support which is shiftable at will to change case. The segment 16 is provided at its sides with upright track members 28 which co-operate through anti-friction balls 29 with oppositely grooved track-ways 30 secured to posts 31 fixed to and rising from the base 1. The sets of balls 29 at the sides of the segment are each controlled 95 by a separator 32.

For limiting up and down movements of the segment along the track-ways or fixed guiding and supporting devices 30, 31, stop devices are provided comprising at each side 100 of the segment an upper step 33 and a lower stop 34, both on the segment itself. Co-operating stop devices 35 and 36 are adjustably secured in pairs to the rear faces of the posts 31. The stop devices 35 and 36 105 are essentially alike. Each is formed with a slot or kerf 37 preferably terminating in an enlarged opening 38. The slots 37 divide

the stopping end of each of the devices 35 and 36 into tongues 39 and 40. The tongues 39 with which the stops are mounted on the segment coöperate directly, are, because of this construction, somewhat yielding or resilient so that both the noise and the jarring incident to the arrest of the segment at the end of shifting movements are minimized. The body portions of the devices 35 and 36 are provided with elongated slots 41 which receive headed screws 42 by which each stop device is adjustably secured to the rear face of the post 31. The stopping face of each tongue 39 is inclined to correspond with the inclined stopping face of the associate stop on the segment, the construction being such that by moving the stop device in or out prior to setting it by the screw 42, the point of arrest of the segment may be varied. The stop devices 35 and 36 are not claimed herein as they are the invention of George A. Seib and form in part the subject-matter of his application Sr. No. 69,601, filed December 31, 1915.

To support the segment and shift it down and up, devices are provided which are connected to lugs 43 extending downward from the segment, one near each end thereof. Said devices comprise a pair of upright links or bars 44, the upper ends of which are pivotally connected by screws 45 to the outer faces of the lugs 43. The lower ends of said links are pivotally connected by screws 46 to the free ends of rearwardly extending crank arms 47, said crank arms being provided with hub portions 48 which fit over and are fixed to a rock shaft 49 bearing at its ends on pivot screws 50 secured in the sides of the base 1. Segment shifting and locking devices are provided which are the sole invention of Charles J. Bond and are disclosed and claimed in his application Serial No. 22,032, filed April 17, 1915. Said devices comprise short forwardly extending crank arms 51 arranged near the ends of the rock shaft 49 and provided with hubs 52 which fit over and are pinned or otherwise secured to the rock shaft 49. Just inside each crank arm 51 a curved arm 53 is arranged, said arm being provided with a slot 54 which receives a headed screw 55 that is threaded into the contiguous arm 51, the arms 53 and 51 being thus adjustably secured together and so that the relation of the arm 53 with the rock shaft 49 may be varied. Said arm 53 is cut out to fit over said rock shaft and take a bearing thereon, thence curving upward, rearward and downward, its rear end carrying a pivot screw 56 on which is mounted a roller 57. Operative on the left-hand roller 57 are lugs 58 and 59 projecting downward respectively from shift key levers 60 and 61. These levers are fulcrumed at their rear ends on a pivot screw 62 which is supported in a U-

shaped bracket 63 that is suitably secured to the under face of the rear portion of the base 1. This bracket has a slotted guiding ear 64 by which the levers 60 and 61 are guided. Each lever is provided with a coiled restoring spring 65 and the lever 60 has a key button 66 while the lever 61 has a key button 67. A right-hand shift key lever 68 corresponding with the shift key lever 61 at the left is provided, the lever 68 bearing on a pivot screw 69 supported by a fixed bracket 70, which bracket is provided with a slotted guide ear 71. The lever 68 has a restoring spring 72 and a key button (not shown). The depression of the key 66 shifts the segment and causes it to be locked in shifted position, while the levers 68 and 61 control the temporary shift of the segment and do not lock it down. The shift locking devices comprise a latch 73 pivoted at 74 to the lever 60 and constructed so that when the key 66 is operated the upper end of the latch is thrown under a fixed abutment 75 by a spring 76 connected to the lower end of said latch 73 and to the lever 60. The latch is released by a pin 77 on the lever 61 which throws the upper end of the latch rearward from under the locking abutment 75 when the key 67 is operated. Normally the segment 16 is maintained in its upper position with the movable stops 34 engaged with the lower stops 36 as illustrated in Figs. 1 and 5, in which position the inner or lower case types 13 are operative. For thus normally maintaining the segment in upper position, spring means are provided comprising a pair of draw springs 78 each connected at its forward end to a pin 79 extending radially downward from the rock shaft 49. The rear ends of the springs 78 are adjustably anchored to screw hooks 80 threaded respectively into projecting ends of the screw pivots 62 and 69 and adjustably set by locking nuts 80a. Suppose the shift key lever 61 is depressed, then its lug 59 will act on the roller 57, depressing said roller and turning the rock shaft 49, stretching the springs 78 and swinging the arms 47 downward, thereby lowering the bars 44 and permitting the segment 16 to slide downward in its bearings until arrested by the engagement of the stops 33 with their associate stops 35. In this position of the segment the upper case types 14 will be effective. On releasing the lever 61 the segment and associate parts will be restored to normal position by the springs 78 and 65. The effect of operating the shift key lever 68 is the same. When, however, the lever 60 is operated the segment will be locked down in upper case position by the latching or locking devices.

To guide the type bars during printing operations, a type guide is provided which is supported on a segmental plate 81 ar-

ranged above the type bar pivots and having ears 82 which receive screws 83 by which the plate is fixed at its ends to lugs 84 on the segment 16. A segmental abutment 85 on 5 the front face of the plate 81 is struck by the type bars at or near the ends of their printing movements. The plate 81 has a depression 86 as shown in Fig. 3 and in said depression is seated a plate 87 which is 10 fixed in place by screws 88. The plate has a central opening 89, the lower portion of which is shaped to provide a pointer 90 which coöperates with the platen scale (not shown). A type opening or slot 91 at the 15 upper end of said plate 87 is adapted to receive the types and guide them to the printing point. At either side of the type opening horizontal wings or guides 92 project forward from the plate 87, which guides are 20 shaped to provide a flaring mouth communicating with the slot 91. The devices 91 and 92 guide the type bars near their free ends during printing while near their pivot ends the type bars are guided by slots 93 in the 25 segment 16 in which they are seated. The plates 81 and 87 coöperate to provide a guide and support for the stem 94 of a ribbon vibrator or guide 95 which comprises in addition to the stem both a head composed of 30 parallel branches 96 diverging from the stem and also guide fingers 97. The combined type guide and ribbon guide device 87 shifts with the support 81 and the type bar segment 16. Through the ribbon vibrator 95 35 is threaded a ribbon 98 which is preferably carried by spools (not shown), said spools being rotatable and controllable by suitable mechanism preferably like that found in the Monarch typewriting machine. The stem 40 94, as shown in Fig. 3, is slidably supported and guided in a way made by depressing the rear face of the plate 87 as indicated at 99, this depression, together with the front face of the plate 81, providing a grooved track 45 for the stem 94. The rear face of the plate 87 is further formed with a vertical depression or slot 100 which registers with a slot or opening 101 cut in the plate 81. The vibrator is actuated by means which co- 50 operate with a pin 102 supported at the rear of the stem by a plate 103, riveted or otherwise secured to the rear face of the stem 94 and terminating at its lower ends in ears 104 which are curled around and clasp the 55 ends of the pin 102. Engageable with this pin 102 is the forward slotted end of an operating lever 105 which is fulcrumed at 106 on a lug 107 depending from the top plate. The rear arm of the lever 105 is 60 slotted, as indicated at 108, and receives an actuating pin 109 that projects laterally from the top of a link 110, the lower end whereof is pivotally connected at 111 to a universal bar frame 112 which is operative 65 by the key levers to pull down the link 110 and operate the lever 105 and the ribbon vibrator. During the vibratory movements the forward end of the operating lever moves up and down in the slot 100, 101. The position of the actuating pin 109 in the slot 70 108 may be varied to vary the extent of throw of the vibrator, this variation being effected by means which comprise a rotary member 113 which is mounted on a ribbon driving shaft 114 and which coöperates with 75 the link 110. To guide the link, devices are provided comprising a slotted guide 115 secured to a comb plate 116 which guides the sub-levers 18.

The universal bar frame 112 comprises a 80 straight universal bar proper 117 underlying the key levers, said bar being secured to curved crank arms 118 which project rearward from a rock shaft 119 having fixed pivots. The pivot 111 is on the middle one 85 of said crank arms of which there are three. Pivoted at 120 to the middle arm is a lever 121 having a pin and slot or lost motion connection 122, 123 with said middle arm. The forward arm of said lever terminates in a 90 lip 124 which is engaged by a device (not shown) operative from the space bar of the machine. The universal bar construction here described resembles generally that disclosed in the patent to Barney No. 893,422, 95 dated July 14, 1908. The explanation of the operation of the universal bar mechanism heretofore described will be deferred until after the description of a supplementary or additional universal bar mechanism which is 100 operative directly by the type bars. The rear arm of the lever 121 is connected by an adjustable two-part link 125 with a dog rocker 126 pivoted at 127 to ears 128 on a stationary bracket 129. The horizontally 105 disposed arm of the rocker is provided with a screw stop 130 having a leather buffer or end portion 131 which is normally maintained engaged with the bottom face of the bracket 129 by a rocker spring 132. A second screw stop 133 carried by the upright arm of the rocker is provided with a leather buffer 134 which coöperates with the rear portion of the bracket 129 to limit operative 110 movements of the rocker. The buffers 131 and 134 lessen considerably the noise due to the arresting of the rocker at the ends of its movements. The rocker carries at its upper end two dogs 135 and 136 which coöperate 115 with a toothed escapement wheel 137, said escapement wheel being operatively connected with a shaft 138 mounted on a stationary bracket 139. As best shown in Fig. 6, a leaf spring 140 is interposed between the tail of the dog 136 and the adjacent face of the dog rocker to which the lower end of said spring is attached. The spring tends to stand slightly away from the face of the dog rocker and its function is to cushion the impact of the tail of said dog with the face of 120 125 130

4

said rocker and thereby lessen the noise due to such impact. The operative connection between the escapement wheel 137 and the shaft 138 comprises a spring-pressed pawl 141, pivotally mounted on a housing 142 fixed to the shaft 138 in the usual way. Said pawl co-operates with a ratchet wheel 143 rigid with the escapement wheel 137. A circular spring guide or cam 144 loosely surrounds said ratchet wheel and in the space between its ends and the pawl 41 normally passes and is held in engagement with the ratchet wheel 143 by the pawl spring 141^a and the pull of the main spring. During letter space advance movements the guide 144 will be carried around with the pawl 141 and the ratchet wheel 143 so that its relation will not be changed. The guide spring 144 has enough grip on the ratchet wheel to remain stationary long enough to enable the left-hand free end of the spring to cam or lift up the pawl 141 at the beginning of a carriage return movement; this lifting of the pawl continuing until it has disengaged from the ratchet wheel 143 as shown in the small view in Fig. 6. Thereafter as backward movement of the carriage is continued, the pawl will turn bodily, forcing the guide 144 ahead of it, said guide slipping around noiselessly over the teeth of the ratchet wheel 143 and maintaining the pawl tooth disengaged from said ratchet teeth, thus avoiding the noise which has heretofore resulted from the backward clicking of the pawl over the ratchet wheel during carriage return movements. The construction involving the spring 144 is *per se* the sole invention of Hubbard N. Josley and is disclosed and claimed in his application, Sr. No. 35,837, filed June 23, 1915. The forward end of the shaft 138 carries a feed pinion 145 which is normally engaged by a feed rack 146 mounted on the carriage 8, 9. Said carriage is normally urged leftward by a motor or spring drum 147 to which it is connected by a strap 148.

The spring drum 147 is connected with the ribbon driving shaft 114 in the usual way found in the Monarch machine, the connection comprising a ratchet wheel 149 mounted at the front face of said spring drum, and also beveled pinions 149^a and 149^b, the first rigid with said ratchet wheel and the second mounted on and driving the shaft 114. Instead, however, of the usual pawl for connecting said ratchet wheel 149 with said spring drum at times when the spring drum turns to draw the carriage in printing direction, a spring 150 of novel construction is secured to the ratchet pawl by a screw 151 and engages at its free end with the ratchet. The spring and pawl construction *per se* is the sole invention of Hubbard N. Josley and is the subject-matter of his application, Sr. No. 35,838, filed

June 23, 1915. During the return movements of the carriage and spring drum the spring 150 will slide lightly over the ratchet teeth and the clicking sound which results in the ordinary construction from the movement of the pawl over the ratchet teeth is in the present instance largely eliminated.

Supplementary universal bar mechanism is provided comprising a curved universal bar proper 152 arranged just below the plate 81 and between the same and the pivot portions of the type bars. Said universal bar 152 is of light stock and is in the form of a segment concentric with the segmentally arranged set of type bars. The front edge of the universal bar is turned inward to provide a contact surface 153 which is in a vertical plane normally forward of the plane of the plate 81, as is clearly shown in Fig. 1. The contact surface or flange which also lends rigidity to the universal bar is engageable by faces or projections 11^a on the type bars 11 by which the universal bar 152 is adapted to be moved bodily rearward in both shift positions of the type bar segment. To this end the universal bar 152 is supported from the plate 81 so that said bar may shift with the type bars and their support. The normal or lower case position of the universal bar is shown by full lines in Fig. 2 while its abnormal or upper case position is indicated by the dotted lines in said figure. In the present instance the universal bar 152 is slidably carried by devices comprising a supporting frame composed of a stem 154 from which diverge branches 155 and 156, said branches being connected at their ends by a cross portion 157. This cross portion is provided with a depression or open top notch 157^a (Figs. 4, 5 and 7) to allow for the up and down movements of the operating lever 105. The inner face of the universal bar 152 is preferably lined with a layer of felt 158, which felt is cut away to permit two ears 159 in which the branches and cross portion of the supporting frame terminate to contact directly with the universal bar proper 152, the latter being suitably secured near its ends to the ears 159 as by riveting. At about the junction of each of the branches 155 and 156 with the cross portion 157 a horizontally arranged and forwardly projecting pin 160 is suitably fixed to the supporting frame, the pins bearing slidably in transverse holes 161 in the plate 81. The rear end of the stem 154 is turned up at one side, as indicated at 162, providing an angle portion in which is received and suitably secured a block 163 perforated as indicated at 164 to bear on a guiding and supporting rod 165, said rod extending horizontally and being fixed at its forward end in the plate 81. Secured in the rear end of said rod is a stop screw 166 which, through

contact of the block 163 with the head of said screw, limits the rearward movements of the universal bar device comprising the universal bar 152 and its supporting frame. 5 Normally the universal bar device is held in forward position by a coiled spring 167 anchored at its forward end to the plate 81 and connected at its rear end to the universal bar frame. It will be understood 10 that the universal bar device is slidably supported on the plate 81 which is rigid with the type bar support, said universal bar device having three triangularly arranged sliding points of support, two at the 15 front where the pins 160 bear in the openings 161 and the other at the rear where the block 163 bears on the rod 165. This construction provides for an easy fore and aft movement of the universal bar device under the actuation of each and all of the 20 type bars and in both lower and upper case positions.

The universal bar frame is connected to the dog rocker 126 by devices comprising an 25 upright lever 168 of the first order which is fulcrumed at 169 to an angular bracket 170 fixed to the rear of the plate 81. The lower arm of the lever 168 is connected by a link 171 to an angular bracket 172 fixed to and 30 depending from the cross portion 157. A horizontally disposed link 173 connects the upper arm of the lever 168 with an angular bracket 174 secured by a screw 175 to the upper arm of the dog rocker 126. The link 35 173 may be readily detached from its pivotal points of connection with the lever 168 and the bracket or arm 174. It will be understood that when the universal bar 152 is operated by any one of the type bars it will 40 move bodily rearward, this movement being transmitted through the link 171 to the lever 168, the lower arm of which will swing rearward and the upper arm forward, the latter arm pulling forward the 45 link 173, with the result that the dog rocker will be actuated. It will also be understood that the connections between the dog rocker and the universal bar 152 shift or move when the type bar segment and said universal bar are shifted, the lever 168 and link 171 shifting bodily and the link 173 swinging or shifting about its connection with the bracket 174 on the dog rocker as a center, there being sufficient lost motion in 50 the parts to permit of these movements.

The universal bar 117 as stated is operated by one part of the type actions, viz., the key levers, and actuates both the escapement devices and the ribbon vibrating devices. The universal bar 152 is operated directly by the type bars, that is, by another part of the type actions, and actuates only the escapement devices, having no effect on the ribbon vibrating devices which are independent of said universal bar 152. The two

universal bars 117 and 152 are preferably constructed to operate in conjunction with each other, both acting on the dog rocker or escapement devices but at different parts of the movement of the latter. In the present 70 instance during the initial portion of the key depression the universal bar 117 is effectively operated, actuating the dog rocker and the ribbon vibrating devices in the usual way. During this portion of the stroke of 75 the type bar the universal bar 152 moves idly, receiving actuation through the connections between it and the dog rocker comprising the link 173 and lever 168. When the type bar reaches the point in its movement toward the platen indicated by the dotted line position in Fig. 1, the portion 11^a of said type bar will pick up the universal bar 152 which, through the described train 80 of connections, will act effectively on the dog 85 rocker to swing the same forward, taking it out of the control of the universal bar 117. In other words, the key lever through the universal bar 117 starts the escapement in motion and the type bar through the universal bar 152 finishes or completes the movement of the escapement. The important result accomplished by this construction is that a practical uniform let-off of the 90 escapement is insured through actuating the 95 escapement from the type bars while at the same time the usual objections to actuating the escapement on this principle are done away with. By employing two universal 100 bars and effecting the initial movement of 105 the escapement devices through the key lever operated universal bar, the type bar is relieved of the retarding effect which would result from striking the universal bar 152 when at rest or in its normal position, and 110 which would be unavoidable if the universal bar 152 alone were employed.

It will be observed that by our present invention we provide in combination with carriage and escapement devices, two co-operative universal bars for actuating said devices, said universal bars being actuated by means controlled by a single key, said means in the present case comprising a type action consisting of a type bar, a key lever 115 and connections between said type bar and key lever; that separate trains of devices connect the universal bars with the dog rocker, which dog rocker is comprised in the escapement devices; that one of said separate trains includes the links 171 and 173 and the intermediate lever 168, while the other train includes the link 125; that one of the universal bars, in the present instance, the straight universal bar, operates 120 means for beginning a movement of the escapement devices while the other, or curved, universal bar operates the means for completing the movement; that the mechanism 125 is so timed that one universal bar initiates 130

- the operation of the escapement and the second universal bar completes the operation, the universal bars being successively actuated; that both universal bars are constantly 5 connected to the escapement devices through the described trains of connections to the dog rocker; that each key lever directly operates one universal bar and indirectly through its connected type bar operates the 10 other universal bar; that one of the universal bars, in the present instance the type bar actuated universal bar, is associated with means for initiating movement of said universal bar prior to its actuation by a type 15 bar; that certain of the escapement devices comprising the dog rocker and the dogs mounted thereon are given an initial movement in one direction by one universal bar, movement in the same direction being completed 20 through and by the other universal bar independently of the first universal bar; that one universal bar actuates both escapement devices and also ribbon vibrating devices, and the other universal bar operates only 25 one of said sets of devices, in the present instance the escapement devices; that there are provided a platen element and a type bar element relatively shiftable to change case in combination with a universal 30 bar shiftable automatically when the case shifting operation takes place and a second universal bar that does not shift but has an unvarying normal position, this last named universal bar being mounted on a stationary 35 part of the machine, while the other universal bar is mounted on one of said elements, in the present case, on the type bar element, segment or shiftable support; and that the shiftable universal bar is connected 40 with a non-shiftable dog carrier or rocker through connections comprising an intermediate lever and two links, said connections shifting with the shiftable universal bar and the segment or type bar supporting 45 element.
- Various changes may be made without departing from our invention.
- What we claim as new and desire to secure by Letters Patent, is:—
- 50 1. In a typewriting machine, the combination of a carriage, escapement devices, and two key operated universal bars for successively operating said devices when a key is actuated.
- 55 2. In a typewriting machine, the combination of a carriage, escapement devices, two universal bars, connections between said devices and said universal bars, and means controlled by a single key for actuating both 60 said universal bars.
3. In a typewriting machine, the combination of a carriage, escapement devices, two universal bars, separate trains of connections between said universal bars and
- said devices, and a plurality of keys each 65 effective on both universal bars.
4. In a typewriting machine, the combination of a carriage, escapement devices, two universal bars, means operated by one of said universal bars for beginning the 70 movement of said escapement devices, and means operative by the other of said universal bars for completing the movement of said escapement devices.
5. In a typewriting machine, the combination of a carriage, escapement devices, two universal bars, means operated by one of said universal bars for beginning the 75 movement of said escapement devices, and means operative by the other of said universal bars for completing the movement of 80 said escapement devices, both said means being operative by a single key.
6. In a typewriting machine, the combination of a carriage, escapement devices, a type bar, a key lever, connections between 85 said type bar and said key lever, and two universal bars operative on said escapement devices, one universal bar being actuated by said key lever and the other by said type 90 bar.
7. In a typewriting machine, the combination of a carriage, escapement devices, a type bar, a key lever, connections between 95 said type bar and said key lever, a universal bar operated by said key lever, connections between said universal bar and said escapement devices, a second universal bar operated by said type bar, and connections between 100 said second universal bar and said escapement devices.
8. In a typewriting machine, the combination of a carriage, escapement devices, a type bar, a key lever, connections between 105 said type bar and said key lever, a universal bar operated by said key lever, connections between said universal bar and said escapement devices, a second universal bar operated by said type bar, and connections between 110 said second universal bar and said escapement devices, said last recited connections operating to withdraw the escapement devices from the control of said first named universal bar.
9. In a typewriting machine, the combination of a carriage, escapement devices, two universal bars both constantly connected to said escapement devices, and a type action operative on said universal bars.
10. In a typewriting machine, the combination of a carriage, a movable element, two universal bars, and means for successively causing the effective operation of both said 120 universal bars on said movable element.
11. In a typewriting machine, the combination of a carriage, escapement devices, two universal bars both constantly connected to said escapement devices, and key op- 125

- erated means for successively causing the effective operation of said universal bars.
12. In a typewriting machine, the combination of a carriage, escapement devices, two universal bars connected to said escapement devices, and a series of type actions; one part of each action operating on one universal bar and another part operating on the other universal bar.
13. In a typewriting machine, the combination of a carriage, escapement devices, two universal bars connected to said escapement devices, and a series of type actions; one part of each action operating on one universal bar and another part operating on the other universal bar, said parts operating on their associated universal bars one in advance of the other.
14. In a typewriting machine, the combination of a carriage, a movable element, two universal bars both operative thereon, type bars, and key levers, the key levers being operative on one universal bar and the type bars on the other universal bar, the parts being timed so that the operations of both universal bars on said movable element are successive.
15. In a typewriting machine, the combination of a carriage, a movable element, printing devices comprising a key lever, and two universal bars, one universal bar being operative directly and the other indirectly by said key lever and both said universal bars being operative to actuate said movable element.
16. In a typewriting machine, the combination of a carriage, escapement devices, type bars, a universal bar operated directly by said type bars, and means for initiating movement of said universal bar prior to its actuation by said type bars.
17. In a typewriting machine, the combination of a carriage, escapement devices, a key operated universal bar for initiating movement of said escapement devices in one direction, and means independent of said universal bar for completing the movement of said escapement devices in the same direction.
18. In a typewriting machine, the combination of a carriage, escapement devices, printing keys, ribbon vibrating devices, a universal bar for actuating both said escapement devices and said ribbon vibrating devices, and a second universal bar operative to actuate only one of said sets of devices, all the printing keys being effective on both universal bars.
19. In a typewriting machine, the combination of a carriage, escapement devices, printing keys, ribbon vibrating devices, a universal bar for actuating both said escapement devices and said ribbon vibrating devices, and a second universal bar for actuating only said escapement devices, all the printing keys being effective on both universal bars.
20. In a typewriting machine, the combination of a carriage, escapement devices, ribbon vibrating devices, a type action, and two universal bars operative by said type action, one universal bar connected both to said escapement devices and to said ribbon vibrating devices and the other universal bar connected only to one of said sets of devices.
21. In a typewriting machine, the combination of a carriage, escapement devices comprising a dog rocker, type bars, key levers connected to said type bars, a universal bar operative by said key levers, connections between said universal bar and said dog rocker, a second universal bar operative by said type bars, and connections between said second universal bar and said dog rocker.
22. In a typewriting machine, the combination of a carriage, escapement devices comprising a dog rocker, ribbon vibrating devices, type bars, a key lever, connections between said type bars and said key levers, a universal bar operative by said key levers, connections between said universal bar and both said dog rocker and said ribbon vibrating devices, a second universal bar operative by said type bars, and connections between said second universal bar and said dog rocker.
23. In a typewriting machine, the combination of a carriage, escapement devices comprising a dog rocker, type bars, key levers connected to said type bars, a universal bar operative by said key levers, connections between said universal bar and said dog rocker, a second universal bar operative by said type bars, and connections between said second universal bar and said dog rocker, the parts being so timed that the first universal bar starts the dog rocker to move while the second universal bar is picked up by a type bar and becomes effective toward the end of the movement.
24. In a typewriting machine, the combination of a carriage, a dog rocker, a type action, a curved universal bar operative by one part of said type action, a straight universal bar operative by another part of said type action, and sets of connections between said universal bars and said dog rocker.
25. In a typewriting machine, the combination of a platen carriage, escapement devices comprising a dog rocker, a segmental series of type bars, a curved universal bar operative by said type bars, key levers connected to said type bars, a straight universal bar operative by said key levers, and connections between both said universal bars and said dog rocker.
26. In a typewriting machine, the com-

- bination of a platen element, a type bar element, said elements being relatively shiftable to change case, escapement devices, a universal bar shiftable automatically when 5 the case shifting operation takes place, and a second universal bar having an unvarying normal position, said second universal bar being independent of the case shifting operation.
10. 27. In a typewriting machine, the combination of a platen, a type bar support shiftable to change case, escapement devices, a universal bar mounted to shift with said type bar support, and a second universal bar 15 mounted on a stationary part of the machine.
28. In a typewriting machine, the combination of a platen, a type bar support, type bars thereon, printing key levers connected with said type bars, escapement devices, a universal bar mounted on said type bar support and operative by said type bars, case shifting means operative on said type bar support, and a second universal bar 25 operative by said key levers.
29. In a typewriting machine, the combination of a platen, shiftable type bars, a shiftable universal bar directly operative by said type bars, key levers connected with 30 said type bars, and a second universal bar operative by said key levers.
30. In a typewriting machine, the combination of a platen, type bars, key levers therefor, a type bar support shiftable to 35 change case, escapement devices, a universal bar mounted to shift with said type bar support, a second universal bar mounted on a stationary part of the machine, and devices connecting both of said universal bars 40 with said escapement devices.
31. In a typewriting machine, the combination of a platen, a type bar support, type bars thereon, escapement devices, a curved universal bar connected to said escapement 45 devices and operative by said type bars, a supporting frame by which said universal bar is carried, means for supporting said
- frame from three points on said type bar support, and means for shifting said frame and said type bar support to change the 50 normal positions of said type bars and of said universal bar.
32. In a typewriting machine, the combination of escapement devices, key operated universal bar devices connected thereto, and 55 a support comprising a rod, said universal bar devices comprising a frame, two pins at the sides of said frame bearing slidably in holes in said support, and an apertured block on said frame in rear of said pins, said 60 block bearing on said rod.
33. In a typewriting machine, the combination of a platen, a segmentally arranged series of type bars, a curved universal bar operative by said type bars, a slidable frame 65 on which said universal bar is mounted, a dog rocker, and connections between said frame and said dog rocker comprising an intermediate lever and two links, one link connecting said dog rocker with said lever 70 and the other link connecting said frame with said lever.
34. In a typewriting machine, the combination of a platen, a segmentally arranged series of type bars, a curved universal bar 75 operative by said type bars, a slidable frame on which said universal bar is mounted, a dog rocker, connections between said frame and said dog rocker comprising an intermediate lever and two links, one link connecting said dog rocker with said lever and the other link connecting said frame with 80 said lever, and means for shifting said type bars to change case, said frame and said connections shifting with said type bars. 85

Signed at Syracuse, in the county of Onondaga, and State of New York, this 31 day of March, A. D. 1915.

CHARLES J. BOND.
HUBBARD N. JOSLEYN.
